United States Patent Office

Des. 177,944
Patented June 5, 1956

177,944

TEAPOT

Peter Schlumbohm, New York, N. Y.

Application June 29, 1955, Serial No. 36,757

Term of patent 14 years

(Cl. D44—26)

FIG. 1.

FIG. 2.

Figure 1 is a side view of a teapot showing my new design.

Figure 2 is a similar view with the teapot rotated 90° from its position in Figure 1.

I claim:

The ornamental design for teapot, as shown.
